UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

BINDING-TERMINAL.

1,321,880.

Specification of Letters Patent. Patented Nov. 18, 1919.

Application filed February 29, 1916. Serial No. 31,102.

To all whom it may concern:

Be it known that I, REUBEN B. BENJAMIN, a citizen of the United States, residing at Chicago, in the county of Cook and State 5 of Illinois, have invented new and useful Improvements in Binding-Terminals, of which the following is a full, clear, concise, and exact description, reference being had to the accompanying drawing, forming a 10 part of this specification.

My invention relates to binding terminals.

One of the objects of my invention is to provide a binding terminal which will be simple in construction and efficient in use. 15

In the drawings, in which I have shown several embodiments of my invention—

Figure 1 is an axial section of a receptacle provided with my improved binding terminals;

20 Fig. 2 is a section on the line 2—2 of Fig. 1;

Fig. 3 is a section on the line 3—3 of Fig. 2;

Fig. 4 is a perspective view of the binding screw;

Fig. 5 is a bottom view of the binding screw;

Fig. 6 is a perspective view of the center contact and its leading in wire;

30 Fig. 7 is an axial section of a different form of receptacle;

Fig. 8 is a section on the line 8—8 of Fig. 7;

Fig. 9 is an axial section showing a different form of binding terminal;

Fig. 10 is a bottom view of Fig. 9;

Fig. 11 shows a bottom view of a modified form of binding screw; and

Fig. 12 is a side elevation of Fig. 11.

40 Referring to the drawings in detail, the receptacle shown in Figs. 1 to 6, inclusive, comprises an insulating base 10, shell and center contacts 11 and 12 supported by the base, and binding screws 13 and 14 for the shell and center contacts.

The shell contact 11 has a flange 15 for securing it to the base and a struck up cup shaped portion 16 forming a pocket or recess for receiving the head of the binding screw 13.

50 The center contact 12 comprises a spring contact portion 17, a base portion 18 secured to the base 10 by means of an eyelet 19, and a struck up cup shaped portion 20 forming a pocket or recess for receiving

the head of the binding screw 14. The 55 binding screws 13 and 14 engage nuts 21 and 22 respectively. The cup shaped portions 16 and 20 are provided with openings 23 and 24, respectively, and the base 10 is provided with passages 25 and 26 through 60 which the leading in wires 27 and 28 are inserted so that their ends will be engaged by the heads of the binding screws 13 and 14.

The binding screws 13 and 14 are identical and each comprises a head 29 which is recessed at 30 to form a curved shoulder 31 for engagement with the end of the leading in wire.

In wiring the receptacle the ends of the leading in wires are inserted through the 70 passages 25 and 26 and through the openings 23 and 24 and into the recesses 30 of the binding screws. As each screw is tightened up its shoulder 31 engages the end of the leading in wire to wrap it around the 75 shank of the screw and to force it tightly against the bottom of the struck up cup shaped portion in which the head of the screw is located. This cup shaped portion prevents the end of the wire from escaping 80 from engagement with the shoulder 31 and holds it in proximity to the shank of the screw.

In the receptacle shown in Figs. 7 and 8 the parts are substantially the same as in 85 Figs. 1 to 6 inclusive except that the passages 32 and 33 for the leading in wires are in the sides of the receptacle instead of in the rear and the openings 34 and 35 are correspondingly positioned.

90 In the form shown in Figs. 9 and 10 the insulating base 36 is provided with a receptacle 37 for the entrance of the leading in wires and with a pair of circular recesses 38 and 39 to receive the heads of the binding screws. Passages 40 and 41 for the leading in wires are provided leading from the central opening 37 to the recesses 38 and 39. In this form the walls of the recesses 38 and 39 prevent the ends of the wires from 100 escaping from engagement with the shoulders 31 of the binding screws and hold them in proximity to the shanks of the screws.

105 In Figs. 11 and 12 the binding screw 44 is recessed on both sides as shown at 45 and 46 so that the engagement of the end of the wire with the head of the binding screw is somewhat facilitated.

Having thus described my invention what I claim as new and desire to secure by Letters Patent is:—

1. A binding terminal construction comprising a threaded binding-screw having a head beneath which the end of the conductor is clamped and having a sweep portion to wrap the end of the conductor about the shank of the screw, and a sheet-metal member having a pocket formed therein to receive the head of the screw and to hold the end of the conductor adjacent the shank of the screw, said sheet-metal member having a passage therein leading to the bottom of said pocket for the entry of the end of the conductor to the bottom of the pocket beneath the head of the screw, said passage being to one side of the axis of said screw.
2. An electrical device comprising a threaded binding-screw having a head be-

neath which the end of the conductor is clamped and having a sweep portion for wrapping the end of the conductor about the shank of the screw, and an integral sheet-metal member comprising a contact portion 25 for engagement with a coöperating contact, said sheet-metal member having a pocket formed therein to receive the head of the screw to hold the end of the conductor adjacent the shank of the screw and having 30 a passage therein leading to the bottom of said pocket for the entry of the end of the conductor to the bottom of the pocket, beneath the head of the screw, said passage being located to one side of the axis of said 35 screw.

In witness whereof, I have hereunto subscribed my name.

REUBEN B. BENJAMIN.
